UNITED STATES PATENT OFFICE.

FRANK E. MORRIS, OF PHILADELPHIA, PENNSYLVANIA, ASSIGNOR OF ONE-HALF TO
JOHN C. BERGNER, OF LANSDOWNE, PENNSYLVANIA.

FORMING APPARATUS.

Application filed March 10, 1922. Serial No. 542,629.

To all whom it may concern:

Be it known that I, FRANK E. MORRIS, a citizen of the United States, residing at Philadelphia, in the county of Philadelphia, and State of Pennsylvania, have invented certain new and useful Improvements in Forming Apparatus, whereof the following is a specification, reference being had to the accompanying drawings.

10 My invention relates to forming apparatus for products of plastic material such as dough and the like, especially, doughnuts or crullers, etc.; and the invention is particularly concerned with the production of such articles by extrusion. Besides forming the articles accurately and regularly, even in the usual hollow or annular configuration of ordinary crullers or doughnuts, I aim to produce them rapidly and conveniently, with minimum labor and expense, and of uniformly good quality and appearance. I also aim to make the operation of the forming apparatus flexibly and conveniently regulable, as regards both size of product and rate of production. I further aim to provide for recharging of the apparatus from time to time as easily and quickly as possible, and likewise for easily cleaning it whenever desirable.

20 How these and various other objects and advantages may be attained in connection with my invention will appear from my description hereinafter of the best apparatus embodying the invention known to me.

30 In the drawings, Fig. I is a vertical sectional view of a doughnut cooker equipped with forming apparatus conveniently embodying my invention,—the section being so taken as to reveal most of the principal parts and mechanisms.

Fig. II is a plan view of the cooking receptacle and certain associated parts and mechanisms, various overlying parts being broken away and removed about as indicated by the section line II—II in Fig. I.

Fig. III is a vertical mid-sectional view through the doughnut-forming means.

Fig. IV is a fragmentary view at right angles to Fig. III partly in section as indicated by the line IV—IV in Fig. III, illustrating the mounting of one of the die members shown in Fig. III.

Fig. V is a fragmentary view from beneath, partly in section as indicated by the

line V—V in Fig. III, illustrating the same point as Fig. IV.

Fig. VI shows a longitudinal mid-section through a pressure regulating device for controlling the size of the doughnuts.

Fig. VII is a front elevation of the regulator, from the right of Fig. VI.

The cooking apparatus here illustrated is of the general type and construction recently marketed by the name "Display doughnut machine," under license from myself and John C. Bergner (and forming the subject of patent applications filed by him, including Serial No. 542,614 filed March 10, 1922, concurrently with this application now Patent No. 1,492,542), so that no very extended description thereof is necessary.

The machine or apparatus shown in Figs. I and II comprises a receptacle structure 1 with an annular trough-like vessel 2 for cooking liquor; apparatus 3 over said vessel 75 for forming and introducing raw doughnuts; a rotating carrier 4 with radial vanes or engagement members 5 for progressing the doughnuts in the liquor during cooking; and additional manipulating means, 80 comprehensively indicated at 6, whereby the fully cooked doughnuts are ultimately discharged or ejected from the cooking liquor and from the machine. As best shown in Fig. II, the uniformly spaced carrier vanes 85 5 radiate from an inner ring 7, and are additionally interconnected at mid-length, by circumferential webs 8; so that as a whole the carrier 4 affords two concentric rows of cooking cells for the individual 90 doughnuts. The carrier 4 is rotatably mounted and centered on the inner wall portion 9 of the annular liquor trough or channel 2, on an annular bearing shoulder 10 about mid-height of said inner wall. 95 Doughnuts are initially introduced into the inner cells in succession, by the former 3, at the station "A," and are progressed around the vessel 2 by the vanes 5. They are then transferred to the radially adjacent outer 100 cells at the station "B," and at the same time inverted, by the suitably stationed manipulating means 6, and are again progressed around the vessel 2 before being finally ejected by such manipulating means 6 at the station "C." In the bottom of the trough 2, beneath the multi-cellular carrier 4, are a series of concentric heating coils

12, for heating the cooking liquor as required.

There is a framework 13 for supporting the receptacle structure 1, the forming apparatus 3, and various associated parts, and also an enclosure 14 which serves to confine fumes arising from the hot liquor, and to enclose and protect the parts and mechanisms beneath the receptacle. As shown, 10 the framework 13 comprises tubular supporting uprights or standards 15 ranged around the vessel 2, and cross-bracing frames 16, 17, 18, connecting them above and below the receptacle. In the upper enclosure wall or roof 19 (which rests and is screwed fast on the top cross-frame 16) is an exit 20 with a discharge conduit 21 for carrying off fumes; and in one of the side walls 22 is an opening 23 for discharge of 15 cooked doughnuts to a subjacent delivery chute 24. In the cooking compartment or chamber of the enclosure 14, over the vessel 2, is a liquor reserve reservoir 25 with a pet cock 26 by means of which the supply in 20 the vessel 2 may be replenished,—either periodically, or continuously, at a rate regulated in correspondence with the rate of loss by evaporation, etc. The reservoir 25 being thus exposed to the hot fumes and the 25 heat of the liquor in the vessel 2, the reserve supply is always kept liquid (if it is a grease solid or thick when cold), and hot enough to obviate undesirable chilling of the liquor in the vessel by it.

30 Referring, now, to Figs. I, II, III, IV, and V, it will be seen that the doughnut forming apparatus 3 shown comprises a cylindrical dough magazine or hopper 30, and a forming device proper 31, of an extruding type, taking dough therefrom. In the 35 present instance, the magazine 30 is removably mounted in a double-walled cylindrical receiver 33, shown as having an external top flange 34. The receiver 33 is mounted 40 or bolted in and beneath a downward flanged opening 35 in the enclosure roof 19 and the cross-frame 16; and the former 31 is removably seated at or in a shouldered opening 36 in the receiver bottom, and 45 protrudes downward therethrough. At both bottom and sides, the receiver 33 has an innerlining of heat insulating material 37 (such as asbestos) that serves to thermally insulate the magazine 30 and protect the 50 dough therein from overheating by the fumes, etc., in the upper or cooking compartment of the enclosure 14. The magazine 30 is removable upward from the receiver 33 through the roof opening 35, and has in 55 its own bottom an outlet 38 for co-operation with and connection to the former intake 39,—which latter extends through the receiver bottom opening 36. As shown, the 60 magazine outlet 38 has a conical neck, and the former intake 39 has a conically flared 65

opening or seat to receive it. The weight of the magazine 30 and its contents being supported largely or entirely by its conical neck 38, a tight joint of the latter with the intake 39 is insured. Any drippings of 70 dough when the magazine 30 is being removed are caught by a flanged annular guard enlargement 40 that extends upward and outward from and around the upper end of the intake 39 and the magazine outlet 75 38.

In order that the dough may be fed from the magazine 30 to the former 31 and extruded from the latter by compressed air, 80 the magazine is provided with a cover 44, held in place by a clamp screw 45 in a yoke 46, whose ends take under an external top ring or flange 47 on the magazine, and is made air-tight by an inset resilient gasket 48 (as of rubber) whose sealing face is recessed or grooved to receive an upstanding annular shoulder 49 on the ring 47. Compressed air (supplied through an air line 50 as hereinafter described) is admitted to the magazine 30 through the nipple 51 85 screwed into the cover 44 and the flexible pressure tubing or hose 52 detachably connected thereto. The flexibility of the hose 52, however, allows the cover 44 to be removed from the magazine 30 for replenishment of 90 the latter with dough without detachment of the air line 50 from the cover. When the cover 44 is to be removed, air pressure can be shut off from the hose connection 52 by means of a stop valve 53. In order 95 to prevent agitation of the dough by the air, and to assure more even feeding, a light dished inner cover 44^a, fitting loosely in the magazine 30, may be kept on top of the mass of dough.

100 As a means of feeding and extruding the dough, air pressure presents the important advantage over many mechanical means of feeding that it obviates agitation or working of the dough, which tends (if very intense or prolonged) to toughen the dough and the doughnuts ultimately produced from it.

105 The forming device 31 shown in Figs. I, III, IV, and V, comprises a tubular discharge element or body 55, whose external shoulder 56 rests on the shoulder of the receiver opening 36, and whose enlarged upper end forms the intake 39,—and also coaxial circular sleeve and disk die elements 110 57 and 58, which are relatively movable to open or close the annular die outlet at the lower end of the tube 55. The body 55 is normally held in place by engagement of 115 bayonet pins 60 thereon beneath the edges of the receiver opening 36, but can be released for removal by turning it to bring said pins into alignment with slots or 120 grooves 61 located a short distance from stop pins 62 on the bottom. The disk 57 is 125 130

suspended from a bridge structure 64 spanning the intake 39, by means of a central stem 65 whose reduced and threaded upper end screws into the rounded central stem portion or boss 66 on the bridge 64; and thus the disk is fixed in position, but detachable for cleaning purposes, etc. The sleeve 57 slides up and down (freely, but with a close fit) on the lower portion of the tube 55, which has narrow external circumferential bearing ridges 67. The lower edge of the sleeve 57 is adapted to telescope over the disk 58 with a fairly close but easy fit, and is externally bevel sharpened to cut or shear off the extruded dough cleanly against the disk periphery. The clearances between tube 55 and sleeve 57 afforded by the ridges 67 not only minimize friction, but also tend to prevent small amounts of dough from packing between the parts and thereby causing the sleeve to stick. As shown in Fig. III, the disk 58 is sharpened with an upward bevel at its edge.

In order that the doughnuts may be formed, released, and introduced in definite correspondence and correlation with the succession of moving engagement members 5, the cutter sleeve 57 may be actuated in like manner; and this may preferably be done directly by the rotary carrier 4 itself. As shown in Figs. I, II, and III, there is an actuating lever for the sleeve 57, comprising a double armed yoke 70 and a tappet arm 71 united by a rockshaft fulcrum 72, which is journalled in a bearing bracket 73 depending from the bottom of the receiver 33. The slotted or forked ends of the lever arms 70 engage diametrically opposite pins 74 projecting from a ridge or band 75 on the cutter sleeve 58, and the detachable inclined and horizontal surfaced cam portion 76 of the arm 71 lies in the path of upstanding studs 77 (with anti-friction balls in their ends) on the vanes 5 of the carrier 4.

During movement of the carrier 4, it wipes past and actuates the former arm 71, by means of the studs 77, so as to depress the cutter sleeve 57 over the disk 58 very quickly each time, close the annular die opening, and sever the extruded annular dough formation. As the end of the cam 76 trips past each stud 77, the cutter sleeve 57 rises again very quickly, and reopens the die outlet. The action is such that the formations are released to drop in horizontal position, so as not to be deformed from their proper shape when they strike the liquor. Also, the interruption and resistance to flow of the dough incident to each cutting operation are very brief and slight, so that maximum capacity is secured.

As shown in Fig. II, a raised annular segmental platform plate 78 (mounted on the trough wall 9) underlies the station "A" and the initial 90° (say) of the inner row

of cells, to prevent the raw doughnuts from sinking below the vanes 5 during the interval before they become buoyant enough (by partial cooking) to rise and float at the surface of the liquor.

The normal width of die opening may be varied and regulated by adjusting a screw 80 (with a lock nut 81) threaded in a rearward extension 82 of the lever arm 71, and normally resting against a buffer seat 83 on the bottom of the receiver 33. As shown in Fig. I, a helical tension spring 84 connected to the rear end of the arm extension 82 raises the cutter sleeve 57 practically instantaneously when the arm 71 drops off each stud 77. The shock and vibration of the hammer blow transmitted to the die 57, 58 from the impact of the screw 80 on the buffer 83 (which may be of leather or other suitable material) counteracts any tendency of the doughnuts to stick to the die elements after severance, and thus insures prompt, clean doffing. Operation of the former 31 may be suspended, when desired, by relaxing the tension spring 84 until it will no longer raise the cutter sleeve 57 after the same is depressed to close the die outlet. As shown, the upper end of the spring 84 is connected to a lever 85 loosely pivoted at 86 to the enclosure roof 19 or the top frame 16. This lever 85 normally rests in a notch of an adjacent bracket 87 at such a height as to keep the spring 84 under adequate tension; but by first lifting the lever 85 from its notch and then shifting it sidewise clear of the bracket, it may be lowered so as to relax the spring completely.

In order to take the forming device 31 apart after the dough magazine 30 has been removed from the receiver 33, it is convenient to relax the spring 84 as just described, and allow the fork ended yoke arms 70 to swing downward until they clear and disengage the pins 74. This releases the cutter sleeve 57 and leaves it free to drop off the tubular element 55. The tubular element 55 may then be conveniently released and lifted from its seat in the receiver aperture 36, and out through the roof opening 35.

As shown in Figs. I and II, the former actuating studs 77 are screwed into socket holes 88 in the carrier vanes 5. By removing or omitting these studs 77 from any desired ones of the vanes 5, the forming apparatus 3 can be pro tanto left unactuated and rendered inactive,—so as not to deposit any doughnuts in the corresponding carrier cells,—and the output of the machine correspondingly reduced. For convenience in thus adjusting and varying the output, a plurality of concentric rows or groups of sockets 88 may be provided, as shown, so that they can be kept differently equipped with actuators 77, according to the different

schedules of production to be maintained at different times. This allows the rate of output to be changed very quickly, by simply shifting the cam piece 76 laterally from a position where it cooperates with one row of studs to one where it will cooperate with a different row. This shifting can be made very readily, by virtue of the screw or bolt and slot connections 89 between the cam piece 76 and the lever 71.

The manipulating means 4, 6 (by which the doughnuts are fed through the cooking apparatus) and the air pump or compressor 90 (by which air for feeding the dough is supplied) may be driven or actuated by a common drive. As shown, power for this purpose is furnished by a prime mover such as an electric motor 91 mounted on the bottom frame 18, in the machinery compartment beneath the receptacle structure 1. In this compartment is a horizontal counter-shaft 93, continuously driven by the motor 91 through reduction gearing comprising a worm wheel 94 on said shaft 93 and a worm 95 therefor on a short shaft 96, and also a reducing belt and pulley drive 97 from the motor 91 to said shaft 96. Through intermittent gearing 99, the shaft 93 drives an upright rotary transmission 30 shaft 100; and this shaft 100 extends up through the midst of the receptacle 1 and is connected to drive the carrier 4 by means of a double propeller arm member 101 fast on the upper end of said shaft 100 and engaging between lugs 102 on the carrier ring 7. The intermittent gearing 99 may be of any suitable character,—such as a worm element 103 with pitchless portions interconnected by an inclined or pitched portion, and a coating gear wheel or disk 104 whose teeth and notches correspond in number to the vanes 5 of the carrier 4. On the rear end of the shaft 93 is a generally oval cam 105 (with an overhung skirt or flange portion 106) that acts through a roller 107 on one arm of a lever 108 whose other arm is connected by a short link 109 with an upright rod 110 mounted and guided for vertical reciprocation between pairs of grooved anti-friction rollers 111 carried on one of the frame posts 15. The rod 110 is connected by a bracket arm 112 and a rod 113 to a bracket 114 which carries the grid-like transfer device 115 and the grid-like ejector device 116 of the manipulating means 6.

As will be understood from Fig. I, the devices 115 and 116 normally lie in a deep pocket portion of the trough 2, below the path of the vanes 5, but are elevated through the superjacent carrier cells during the intervals of rest of the intermittently rotating carrier 4. When so raised, the grids 115, 116 are swung outward on their pivots 117 in the bracket 114 sufficiently to transfer, turn, and eject the doughnuts. This swing-

ing is effected by engagement of hooks 118 (pivoted to the grids 115, 116 beyond their pivots 117) beneath the adjacent carrier web 8 and with a stop 119 on the outer receptacle wall, respectively. As the bracket 114 descends again, the devices 115, 116 are quickly retracted by helical tension springs 120 connected between them and said bracket.

As shown in Fig. I, the cylinder of the air pump 90 is pivoted to the frame 18 at 121, and its piston rod 122 is connected to a crank 123 fast on the front end of the shaft 93. The pump 90 discharges through a tube 124 to an air storage and pressure equalizing reservoir 125, whence the line 50 (extending up through one of the posts 15) conveys air under pressure to the forming apparatus 3 via a regulator 126 and the flexible tubing 52, etc.

By actuating the air supply means at 90 and the severing means at 31 (by which the die outlet from the container 30 is automatically closed, and the dough extruded therefrom severed, periodically at regular intervals (from a common drive, as in the arrangement shown and described, the output of the pump is harmonized with the demand for air as affected by any variations in speed of the motor 91, for example.

As shown in Figs. VI and VII, the regulator 126 is of a bleed or constant pressure relief valve ("safety-valve") type, comprising a conical valve 127 in a barrel housing 128. This valve 127 is continually urged toward its rather wide conical seat 129 by a helical compression spring 130, acting between the valve and a screw plug abutment and guide 131 adjustable in the other end of the housing 128. The valve stem 132 has longitudinal air passages 133, 134, the latter of which obviate formation of any air cushion in the bore of the guide 131. Whenever the air pressure in the system becomes very slightly excessive, it forces the valve 127 off its seat 129 and escapes through the ample vents 135, shown as opening through the seat. A pointer 136 on the plug 131 operates with a graduated scale segment 137 on the housing 128. By a proper adjustment or setting of the initial tension of the spring 130, the device can be made to maintain any desired constant pressure in the system, and the rate of extrusion of the dough thus varied and regulated very accurately, according to the size of doughnuts desired, and irrespective of the rate of production to be maintained.

A pressure gauge 138 connected to a four-way fitting 139 through which the tube 52 and the device 126 are connected to the pipe line 50 affords a convenient indication of the air pressure actually existing in the system, and applied to the dough in the container 30, at any time.

As shown in Fig. I, the machinery in the compartment beneath the receptacle structure 1 is protected against objectionable heating from the latter and from the liquor heating means by interposition of a horizontal diaphragm extending across the enclosure 14 just below said structure 1, and here shown as consisting of a metal plate 140 covered with a layer of thermo insulating material 141, such as asbestos, for example.

Having thus described my invention, I claim:

1. Forming apparatus of the character described comprising a container with an annular die outlet and automatic means for closing said outlet at regular intervals and thereby shearing material extruded therefrom, in combination with means for applying air pressure to the material in said container, and for regulating the pressure so applied to control the size of the extrusions periodically severed as aforesaid.

2. Forming apparatus of the character described comprising a container with an annular die outlet and automatic means for shearing the material extruded therefrom at regular intervals, in combination with means for supplying air under pressure to said container, and bleed means for regulating and controlling the application of pressure to the material and the size of the extrusions periodically severed as aforesaid.

3. Forming apparatus of the character described comprising, in combination, a container with an annular die outlet; means for periodically shearing the material extruded from said outlet; a compressed air system for applying pressure to the material in said container, including an air pump; means for actuating said pump and said severing means from a common drive; and bleed means for regulating the application of pressure to the material to control the size of the extrusions periodically severed as aforesaid.

4. Forming apparatus of the character described comprising a container with an annular die outlet; means operating exteriorly of said container for automatically closing said outlet at regular intervals and thereby shearing annular formations of material ex-

truded therefrom; and means for applying air pressure to the material in said container, and for regulating the pressure so applied to control the size of the extrusions severed as aforesaid.

5. Doughnut forming apparatus comprising a former for producing the annular dough formations, a receiver with outlet to said doughnut former, and a removable dough magazine in said receiver having an outlet extending to the former through the receiver outlet.

6. Doughnut forming apparatus comprising a receiver with apertured bottom; a removable doughnut former seated in and protruding through said aperture; and a separately removable dough magazine in said receiver having an outlet for cooperating with said former.

7. Doughnut forming apparatus comprising a receiver with apertured bottom; a removable doughnut former seated in and protruding through said aperture; and a separately removable dough magazine in said receiver for supplying said former.

8. Doughnut forming apparatus comprising a receiver with outlet to a doughnut former; a removable dough magazine in said receiver having an outlet for supplying the former through said receiver outlet; and means at and around said receiver outlet for catching drippings from the magazine outlet when the magazine is removed.

9. Doughnut forming apparatus comprising a receiver with apertured bottom; a removable dough magazine in said receiver having an outlet for supplying a former; and a separately removable former seated in said aperture having its intake enlarged around the magazine outlet to catch drippings therefrom when the receiver is removed.

10. Doughnut forming apparatus comprising a cooking chamber and a thermo insulated receiver therein with outlet to a doughnut former, and a dough magazine in said receiver having an outlet for supplying the former through the receiver outlet.

In testimony whereof, I have hereunto signed my name at Philadelphia, Pennsylvania, this 8th day of March 1922.

FRANK E. MORRIS.
